(57) **CLAIM**

The ornamental design for a combination folder paper towel and dispenser therefor.

DESCRIPTION

FIG. 1 is an exploded perspective view of a combination folded paper towel and dispenser therefor showing my new design with the paper towel shown withdrawn from the dispenser;

FIG. 2 is an alternate perspective view thereof, showing the paper towel within the dispenser;

FIG. 3 is a front elevational view thereof, the rear elevational view being a mirror image thereof;

FIG. 4 is a left-side elevational view thereof;

FIG. 5 is a right-side elevational view thereof;

FIG. 6 is a top plan view thereof; and,

FIG. 7 is a bottom plan view thereof.
